UNITED STATES PATENT OFFICE

103,482

DESIGN FOR A BATHTUB

John A. Callahan, Detroit, Mich., assignor to
Briggs Manufacturing Company, Detroit,
Mich., a corporation of Michigan

Original application April 26, 1935, Serial No.
D. 56,586. Divided and this application No-
vember 21, 1935, Serial No. D. 59,688

Term of patent 14 years

To all whom it may concern:

Be it known that I, John A. Callahan, a citizen
of the United States, residing at Detroit, county
of Wayne, State of Michigan, have invented a
new, original, and ornamental Design for a
Bathtub, of which the following is a specifica-
tion, reference being had therein to the accom-
panying drawing, forming a part thereof, in
which there is shown a perspective view illus-
trating my new design for a bathtub. The pres-
ent application is a division of my co-pending
application Serial No. D. 56,586, filed April 26,
1935.

The dominant feature of the design consists
in the widened portion along the top rim at the
front edge of the tub in combination with the
panelled side and end walls each consisting of
a wide upper panel and a narrow base panel, the
outer surfaces of the panels being in the same
vertical plane and within the confines of the rim
and the relative proportions of the panelled areas
to each other as shown.

I claim:

The ornamental design for a bathtub substan-
tially as shown and described.

JOHN A. CALLAHAN.
